SANITARY DRINKING SPOUT AND BOTTLE CAP

Raymond E. Simons, Fairview, Caseyville Township, St. Clair County, Ill.

Application February 8, 1938, Serial No. 189,393

3 Claims. (Cl. 215—73)

This invention relates to a sanitary drinking spout and bottle cap and has for an object to provide an integral spout and cap which may be readily withdrawn out of the neck of the bottle 5 to provide a drinking spout which is sanitary in use and does not come into contact with any part of the bottle which has been subjected to the touch of human hands in handling the bottle.

A further object is to provide a device of this 10 character which will be inexpensive to manufacture, which will maintain the contents of the bottle leak-proof until used, which will be strong and durable and which will not easily get out of order.

15 With the above and other objects in view the invention consists of certain novel details of construction and combinations of parts hereinafter fully described and claimed, it being understood that various modifications may be resorted to 20 within the scope of the appended claims without departing from the spirit or sacrificing any of the advantages of the invention.

In the accompanying drawing forming part of this specification,

25 Figure 1 is a longitudinal sectional view through a bottle neck showing a sanitary drinking spout and bottle cap constructed in accordance with the invention, in applied position in the neck.

Figure 2 is a longitudinal sectional view of a 30 bottle neck and showing the spout and cap withdrawn from the neck to permit consumption of the contents of the bottle.

Figure 3 is a longitudinal sectional view of the 35 drinking spout and cap taken on the line 3—3 of Figure 2.

Figure 4 is a plan view of the drinking spout and cap.

Referring now to the drawing in which like 40 characters of reference designate similar parts in the various views, 10 designates a bottle neck having a bead 11 provided with a seat 12 and having a stop shoulder 13 provided on the inner wall of the neck below the bead.

The drinking spout 14 is preferably formed of 45 paper in the form of a split cylinder having a rolled bead 15 at the bottom, the edges 16 of the split being substantially close together at the bead and flaring upwardly from the bead to the extreme upper edge 16 of the spout.

50 A cap 17 also formed of paper is secured by stapling as shown at 18 to a tab 19 which projects above the top edge 16 of the spout, there being a

line of perforations 20 in the spout extending in alignment with the tab to permit easily tearing off of the tab. The tab is flexible and may be swung downwardly out of the way when the spout is to be used, the beginning of such swinging movement being shown in Figure 3. A finger hold 21 is formed in the outer surface of the cap to permit the cap being readily removed from the bottle neck to form a grip for withdrawing the spout 14 outwardly until the bead 15 lodges 10 against the stop shoulder 13 in which position of the parts the spout may be conveniently used for drinking from bottles such as milk bottles, pop bottles and other beverage bottles.

It is understood that the spout, cap and lip may 15 be formed from a single blank of material and the staple 18 eliminated.

From the above description it is thought that the construction and operation of the invention will be fully understood without further explanation.

What is claimed is:

1. The combination with a bottle neck having a bead provided with a seat and provided with a stop shoulder on the inner wall below the seat, of 25 a split cylindrical spout, a bead on the bottom of the spout engageable with said stop shoulder to limit withdrawal of said spout from the neck, and a cap hinged to the free end of the spout and adapted to seat in said seat in the bottle neck to 30 seal the bottle.

2. The combination with a bottle neck having a bead provided with a cap seat and provided below the cap seat on the inner surface with a stop shoulder, of a split cylindrical spout slidably 35 mounted in said neck and limited in outward movement from the neck by engagement with said stop shoulder, a tab on the upper edge of the spout, and a cap on the free end of the tab, said tab permitting the cap being rocked away from 40 the spout when the spout is withdrawn to be used in drinking from the bottle.

3. The combination with a bottle neck, of a split cylindrical spout slidable longitudinally in the bottle neck, a tab projecting from the upper 45 edge of the spout, the spout being weakened in prolongation of said tab to permit the tab being bent away from the spout when the spout is withdrawn to be used when drinking from the bottle, and a sealing cap for the bottle neck carried by 50 said tab.

RAYMOND E. SIMONS.
